UNITED STATES PATENT OFFICE.

WILLIAM D. MOORE AND WALTER MORGAN, OF BIRMINGHAM, ALABAMA, ASSIGNEES,
BY MESNE ASSIGNMENTS, TO SAND SPUN PATENTS CORPORATION, OF NEW YORK,
N. Y., A CORPORATION OF DELAWARE.

METHOD OF AND APPARATUS FOR CENTRIFUGALLY CASTING METAL BODIES.

Application filed August 7, 1923. Serial No. 656,180.

This invention relates to the art of making metal castings, and more particularly to a method of and apparatus for centrifugally casting hollow metal bodies such for example as ferrous pipe; and has special reference to the provision of improvements in a method and apparatus as disclosed in the patent of William D. Moore, No. 1,471,052, granted October 16, 1923.

10 The principal object of the present invention resides in the production of an improved centrifugal casting machine of the nature disclosed in said co-pending application and of an improved method of operating the same in which a casting operation may be effected with increased efficiency and with greater economy.

More specific objects of the present invention comprehend the provision of an improved method of controlling the speed of rotation of the rotary or centrifugal mold, of charging the mold with molten metal and imparting to the same a movement supplementary to the rotary movement for effecting an even distribution of the metal in the mold while changing and predetermining the speeds of rotation thereof; the further provision of an apparatus whereby the changed and predetermined speeds may be 20 automatically obtained with great convenience and by means of unskilled labor; the further provision of an improved means for imparting the supplementary movement to the mold whereby a substantially vibrationless casting operation may be obtained with the fewest operating steps; the further provision of an apparatus in which improved means are provided for transferring the mold flasks to and from the machine; the further provision of means for protectively housing the machine arranged to be movable to permit transfer of the molds; and the production of an apparatus in which a large number of the operations to produce a 30 cast such as the control of the speeds of the mold, the pouring of the metal, the manipulation of the mold to effect the desired metal distribution, the operation of the means for transferring the molds to and from the machine, the operation of the mold housing or hood, may be performed and controlled with great ease and convenience by a single unskilled operative located at a remote safety station.

Further and correlated objects of the present invention include the provision of a mold transferring device for centrifugal casting machines constructed to permit equal facility for moving the molds into and out of the casting machine; the further provision of a housing or hood for the machine which carries part of the supporting means for the rotary mold, the said housing and the supporting means being so constructed as to permit of stably supporting the mold and supporting the same for a smooth and vibrationless operation; the further provision of an improved charging means for the mold; and the still further provision of a refractory rotary mold constructed to provide an all refractory surface at the spigot as well as at the bell end of the mold.

To the accomplishment of the foregoing and such other objects as may hereinafter appear, our invention consists in the methods, the steps and the elements and their relation one to the other, as hereinafter particularly defined in the claims, reference being had to the accompanying drawings which show a preferred embodiment of our invention and in which:

Figure 1 is a plan view of the casting machine,

Figure 2 is an elevational view of the same partly in section,

Figure 3 is a cross-sectional view taken on the line 3-3, Figure 1,

Figure 4 is a transverse sectional view on the line 4-4, Figure 3,

Figure 5 is a cross-sectional view taken on the line 5-5, Figure 1, and showing the parts in operative position,

Figure 6 is a view of the same on a reduced scale showing the mold and hood in elevated position,

Figures 7 to 9 are sequential views showing the mechanism for automatically controlling the speed of operation of the mold in certain stages of the casting operation,

Figure 10 is a graphical view showing the manner of controlling the speeds of operation of the mold,

Figure 11 is a view of apparatus used for cooling the casting,

Figure 12 is a detail view showing the apparatus for producing an all refractory surface for the mold, and

Figures 13 and 14 are side and front ele-

vational views respectively of the means employed for controlling the pouring operation and for imparting the supplementary movement to the mold.

As described in the aforementioned patent the method of centrifugally casting hollow metal bodies to which the present invention appertains includes the steps of charging a rotary mold with molten metal and in co-ordinately operating the mold by imparting thereto a motion supplemental to the rotary motion thereof while the molten metal is still in a fluid state so as to effect a uniform distribution of the metal in the mold to produce a uniform and homogeneous casting. More specifically, in the practice of this method a rotary mold is charged with molten metal and is rapidly but quietly moved from a position slightly inclined to the horizontal to a substantially horizontal position while the metal is still in a molten free condition. Referring now in detail to the drawings, the apparatus employed for carrying out these steps of the method preferably comprises a frame or bed 10 which may be a unitary casting removably supporting a rotary mold generally designated as 11 and movable between inclined and horizontal positions about an axis preferably adjacent that is near one end of the bed, the bed being for this purpose provided with the trunnions 12, 12, journalled in spaced bearings 13, 13, which may be securely bolted to the spaced concrete piers 14, 14, the movement of the bed being guided by means of the spaced guide standards 15, 15, firmly secured to a foundation 16.

The mold 11 preferably comprises a refractory lined rotary mold which includes a flask 17 having a plurality of perforations 18 distributed over the body of the same and forming vent holes for the gases and steam generated during a casting operation, the said flask being provided with a refractory lining such as the moist sand lining 19, which lining is preferably surfaced with a facing 20, (see particularly Figures 1 and 4) the moist sand lining preferably having the composition described and claimed in the co-pending application of William D. Moore for composition of matter for molds, Serial Number 623,650, filed March 8, 1923. For rotating the mold, a driving means 21 which preferably comprises an electric motor is provided, and is mounted on the bed 10 at one end thereof, the said motor being preferably arranged co-axially with the mold 11 and movable to and from the mold to cause the coupling and uncoupling of the motor for permitting the transfer of the mold to and from the casting machine, as will be described more in detail hereinafter.

As heretofore mentioned, one of the prime objects of the present invention relates to the provision of an improved method of

operating the mold and of imparting a supplementary movement thereto, the method consisting in the control of the speed of rotation of the rotary mold and in the charging of the mold with molten metal, imparting to the same the supplementary movement for effecting an even distribution of the metal in the mold while changing and predetermining the speeds of rotation thereof. The improved steps in the method are shown graphically in Figure 10 of the drawings, in which the control of the speed of the mold is shown related to the pouring operation and to the step of levelling the mold or moving the mold from the inclined to the horizontal position, the graph representing the speeds of rotation of the mold with time as the abscissa and speed as the ordinate. For purposes of explicit description, we have denoted the actual speeds of operation and the relative time factors, this data applying more particularly to the production of six-inch pipe, and it will be understood that the relative times and speeds are given by way of illustration only and not by way of limitation, and may be varied with considerable latitude for the different size pipes.

Referring still to Figure 10 of the drawings, in carrying out the steps of the method the mold is first moved to a position inclined to the horizontal, and is then started revolving at a low speed as represented by the line O—A, and for six-inch pipe this may be about 100 revolutions per minute. The pouring of the metal then commences as represented by the point X on the line X—Z, or the pouring may commence as the mold is started revolving, and the mold is continued at the low speed of operation as shown by the line A—B during the pouring operation. After the greater part of the metal has been delivered into the mold, and more specifically after approximately 75% of the time of the pouring operation, the speed of rotation of the mold is increased as represented by the line B—C and simultaneously the mold and the bed carrying the same are lowered to the horizontal position as represented by the arrowed line J—K. For the six-inch pipe, it is desirable that the time of levelling of the mold should be about three seconds, and during this time the speed of the mold is rapidly increased until it reaches a high speed, which for six-inch pipe may be approximately 900 R. P. M., which speed is attained within a second or two after the machine reaches the horizontal position, the maximum speed being indicated by the point D on the line BCD. The pouring of the metal continues uninterrupted during this levelling period, and the last metal from the ladle reaches the mold about the time the machine reaches the horizontal position, this being indicated by

the relative positions of the arrowed lines J—K and X—Z. Immediately after the high speed of rotation has been reached, the speed of rotation of the mold is rapidly reduced to an intermediate speed, such for example as 600 R. P. M., as represented by the line D—E, at which speed the mold is allowed to revolve for approximately one minute as indicated by the line E—F. The speed of the mold may then be reduced to about 500 R. P. M., as indicated by the line F—G, and this speed is maintained for approximately one minute as shown by the line G—H, after which the speed is reduced to a medium speed, which may be about 400 R. P. M., as indicated by the line H—I, and revolved at this speed until the metal assumes a congealed state or has solidified sufficiently to permit removal of the mold from the machine, the time of running the mold at the medium speed being indicated by the line I—L, after which the speed is reduced and the machine stopped, as indicated by the line L—N.

It will thus be seen that in the practice of the method, the mold is first rotated at a low speed while in the inclined position, and the speed of rotation increased to a high point during the levelling of the mold, after which the speed is reduced in steps to a medium speed and maintained thereat until the metal congeals. It will be further evident that in the practice of this method the pouring operation is continued while the mold is in the inclined position and during the period of levelling of the mold, and that more particularly the greater part of the pouring operation takes place while the mold is rotated at a low speed and is preferably in the inclined position, and the remainder of the pouring takes place during the levelling of the mold and preferably at the increasing speed thereof. It has been empirically found that this control of the speeds and these inter-relations of the speed of the mold, the levelling of the mold, and the pouring of the metal, produce the best casting results.

For the purpose of permitting the carrying out of the steps of the method by means of unskilled labor and with working precision, we provide apparatus whereby the changed and predetermined speeds may be in part automatically and in part manually obtained. More specifically, we provide apparatus constructed for controlling the speeds automatically in the initial stages of the casting operation such as during the pouring and levelling steps and for permitting manual control of the speeds in the later stages such as during the congealing of the metal and the cooling of the casting.

The apparatus we prefer to employ for automatically and manually controlling the speeds, is shown particularly in Figures 1

and 7-9 of the drawings, this apparatus preferably comprising a motor controller 22 located at a remote control station generally designated as S (see Figure 1), the said motor controller being connected to the main line 23 controlled by means of the manually operable switch 24, the said controller being electrically connected to the motor 21 by means of the connecting line generally designated as 25. Cooperating with the controller and more particularly with the lever 26 thereof, we provide means which is operated by movement of the bed 10, the said means comprising an operating arm 27 attached to the bed at the motor end thereof, a link 28 adjustably connected to the operating arm as by being attachable thereto selectively at any of the points 29, the said link being provided with a loop member 30 which receives the handle 31 of the controlling lever 26, the association of these parts being such that the bed 10 may be moved from a horizontal to an inclined position without moving the handle 31, and so that when the bed is moved in the reverse direction, that is, from the inclined to the horizontal position, the handle 31 is operated simultaneously to increase the speed of the mold and is operated so that a predetermined high speed is attained after the bed has reached the substantially horizontal position, the association being furthermore such that after the levelling of the bed and the mold thereon, the speed of the mold may be manually controlled.

This association and operation is shown in Figures 7 to 9, Figure 7, showing the bed 10 in the horizontal position, Figure 8 in the inclined position prior to a casting operation, and Figure 9 in the horizontal position after the levelling step. When the casting machine is in the horizontal position as shown in Figure 7, the control lever 26 is positioned so that when the main line switch 24 which is normally open is closed, a predetermined low speed of operation is effected such as 100 R. P. M., in the illustration above given. In Figure 7, the lever 26 is fixed relatively to the dial 32 so as to obtain this predetermined low speed. As the bed 10 is moved from the horizontal position shown in Figure 7 to the inclined position shown in Figure 8, by means which will be described in detail hereinafter, the operating arm 27 moves downwardly about the pivotal axis 12, causing the downward motion of the operating link 28. The loop in this link 28 slides along the control lever handle 31 without imparting any motion to the control lever 26, the adjustment of the operating link being such that just as the machine gets to its predetermined inclined position, the shoulder 33 in the link drops in under the control lever handle 31 as clearly shown in Figure 8 of the drawings. As before indicated, the

- adjustment of the lever 26 is such that in this position of the operating link 28, the control lever is located in a predetermined position to cause the motor 21 to revolve the mold at a low speed, which in the example given may be approximately 100 R. P. M., and may be adjusted to give any one of several slow speeds when the main line motor switch 24 is closed.
- With the parts in the position shown in Figure 8 of the drawings, the pouring operation is begun. The pouring of the metal may be carried out by a hand poured operation, but in the preferred practice of the invention, the pouring is accomplished automatically and is controlled by the operator at the station S as will be described more in detail hereinafter. Simultaneously with or previous to the pouring of the metal into the mold the operator closes the main line switch 24 and the mold revolves at the low speed. When the greater part of the charge has been introduced into the mold, and in the illustration given when about 75% of the molten metal has been poured into the mold, the machine is lowered to the horizontal position, the action of lowering the machine automatically and simultaneously imparting an increased speed to the motor, this latter being accomplished by the movement of the control lever 26 from the position shown in Figure 8 to the position shown in Figure 9, the movement of the bed 10 to the horizontal position shown in Figure 9 causing the upward movement of the operating arm 27 and the link 28, the shoulder 33 of the loop member 30 engaging the lever handle 31, causing the lever to rotate for increasing the speed of rotation of the mold, as will be obvious. The parts of the apparatus are so relatively arranged that when the bed arrives at the horizontal position, the control lever 26 is positioned to produce a relatively high speed, such for example as 900 R. P. M.
- Immediately after the machine reaches the horizontal position, the operator shifts the link 28 about its fulcrum point 29 to disengage the shoulder 33 from the underneath side of the control lever handle, and then rotates the handle to slow down the speed of the motor to about 600 R. P. M. After running at this speed for a time, the control lever is further rotated to reduce the speed to about 500 R. P. M., in the example given, and thereafter the medium speed of about 400 R. P. M. is produced, this speed being continued until the metal assumes a congealed state. The control lever 26 is thereafter returned to its position shown in Figure 7, after which the main line motor switch 24 is opened and the machine stopped. The flask is then removed from the machine and another one inserted, and the operation is ready to be repeated.
- If desired, the speed indicator 34 with its

corresponding generator 35 may be provided for indicating the exact speeds attained, thus furnishing a means for accurately adjusting the various control elements and for guiding the operator in manually controlling the machine in the later stages of operation. In this construction it will therefore be apparent that the critical points of changing speeds and the exact speeds desired are automatically obtained and are synchronized with the lowering operation and with the charging operation of the machine in a simple and efficient manner.

It will be readily appreciated that it is highly desirable to move the bed and the parts carried thereby from the tilted to the horizontal position smoothly and without vibration, especially since the levelling must be accomplished within a few seconds. One of the important improvements of the present invention resides in the provision of means whereby this can be accomplished and the casting operation carried out in a substantially vibrationless manner. To effect this, we provide a fluid operated means which is preferably remotely controlled, and in the preferred practice controlled by means at the station S, the said fluid operated means comprising the hydraulic cylinders 69 and 70 provided with the operating plungers 91 and 72 respectively, the cylinders being firmly planted on the concrete bases 73 and 74 respectively, and connected for operation to the control valve 75 at the station S by means of the control line 76. The plungers 71 and 72 are preferably provided at their upper ends with the rollers 77 and 78 respectively, which are adapted to engage the bed, as clearly shown in Figures 1 and 2 of the drawings, at the remote end thereof, for moving the bed between the inclined and horizontal positions. By the provision of this means it has been found that the bed and parts carried thereby may be rapidly yet smoothly manipulated or levelled without creating undesirable vibrations, a substantially vibrationless operation being obtained.

As heretofore indicated, after a casting operation has been effected, the mold with its casting is removed from the machine and is replaced by a new mold ready for another casting operation. For the transfer of the molds in and out of the casting machine, we have provided an improved apparatus which is preferably remotely controlled and operated from the control station S, the said apparatus being constructed so as to permit equal facility for rolling the molds to or from the machine. Referring now to Figures 1, 2, 5 and 6 of the drawings, we show the improved transfer apparatus which comprises a mold elevating means in the form of the elevating track rails 36, 36, each pivotally mounted at one end on the 130

spaced standards 37, 37, and provided at the other end with a mold embracing portion 38, the said track rails being movable from an inclined descended position as shown in Figure 5 to an elevated horizontal or level position as shown in Figure 6, a stop bolt 39 pivotally attached to the rail mechanism and provided with a head 40 for engaging the underneath wall of the bed 10 being provided for limiting the upward movement of the track rails to the straight level or horizontal position, this position being desired so that the molds may with equal facility be rolled from the machine to the track rails and from the rails to the machine. The molds may be removed from the rails 36, 36, to the car 41 movable on the track rails 42 or by any other means such as by crane or overhead trolley.

20 The means for operating the elevating track mechanism preferably comprises fluid operated means controlled by the operator at the station S, the said fluid operated means being conveniently carried by so as to be movable with the movable bed 10. Still referring to Figures 1, 2, 5 and 6 of the drawings, this fluid operated and control mechanism preferably comprises the spaced hydraulic cylinders 43; 43, one for each elevating rail, each cylinder being securely bolted to the bed 10 as at 44. (see Figures 5 and 6). To the said cylinders 43 are connected the hydraulic control lines 45 connecting the control valve 46 to the flexible branch lines 47, 47, control of the valve 46 by the operator being effective for causing the ascent and descent of the plungers 48, each of the plungers being provided with a terminal roller 49 cooperating with a projecting portion 50 which may be formed integrally with a track rail 36 for effecting the elevating and lowering of the track rails.

45 For efficiently supporting the mold for rotation in the casting machine while permitting a quick interchange of molds and for protectively housing the mold during a casting operation, we preferably provide roller supporting means for the mold associated with a housing or hood which is movable on the bed of the machine, the said supporting means including sets of supporting rollers spaced longitudinally of the machine, each set comprising preferably two lower rollers 51 and 52 journalled in the bearing members 53 and 54 securely bolted to the bed of the machine and a top roller 55 journalled for adjustment in a housing 56 which is firmly attached to the top of a hood 57, the latter being hingedly mounted on the bed 10 by means of the hinges 58.

60 Each of the molds 11 is provided with the spaced bands 59 and 60, the band 59 having a concave face and the band 60 preferably having a straight face, the rollers being complementally contoured, one of the rollers

55 being provided to this end with a convex face and the other roller 55 with a straight operating face, as will clearly appear from a consideration of the drawings.

65 In the preferred construction, the hood 57 is made of sufficient weight to cause the rollers 55 carried thereby to act gravitationally on the flask 17 for stably supporting the same for rotation, the construction and arrangement being such that all need for 70 clamping the hood in position is dispensed with, and the casting proceeded with, with greater dispatch.

75 For compensating for the difference in construction and behaviour of different flasks, each of the rollers 55 is preferably adjustably mounted on the hood 57, and in the preferred construction these rollers are floatingly mounted, it having been found in the operation of the machine that this floating condition is desirable rather than a rigid condition, the construction permitting the rotation of the flask without binding and substantially without vibration. The adjustable and floating mounting for each of 80 the rollers preferably comprises an adjusting nut 61 externally threaded as at 62 and adjustably received by the internally threaded portion 63 of the roller housing 56, the said adjusting nut being movable by means of the 85 handles 64, adjustment of the nut being effective for causing the engagement of the roller sleeve 65 with the shaft 67 and brushing 66 surrounding the roller shaft 67 at one end thereof, the roller 55 being mounted 90 for free rotation on the said shaft. For producing the floating condition, a clearance is provided between the top of the adjusting nut 61 and a retaining ring 68 which is threadedly received by the top of the roller 95 sleeve 65. By this means, either or both of the rollers may be adjusted to fit the flask inserted in the machine, with the adjustment such that the flasks are supported 100 for free rotation substantially without 105 vibration.

110 It has been found very desirable to control simultaneously the movement of the hood 57 and the mold elevating means 36 and to place the operation of these parts 115 under the control of a single operative. To these ends, we provide means which is operable for raising the hood 57 simultaneously with the elevating of the flask 17 when it is desired to move a mold from the 120 machine and to lower the hood simultaneously with the lowering of the flask onto the supporting rollers 51 and 52 when a new mold is placed in the machine. To accomplish this, each of the mold elevating arms or elevating rails 36 is provided with a preferably curved extension arm 79 provided at its end with a roller 80 which engages the inner wall of the hood 57, so 125 that when the plungers 48 are operated to 130

cause the elevation of the lifting rails 36, the roller 80 rides in engagement with the inner wall of the hood and raises the same from the position shown in Figure 5 to that shown in Figure 6, the mold 11 being thus moved into position as shown in Figure 6 for quick removal from the machine. When a new mold is replaced into the position shown in Figure 6, the reverse operation 10 of the plungers causes the simultaneous lowering of the lifting rails 36 and the hood 57 to the position shown in Figure 5, as will be apparent.

As heretofore mentioned, a consideratum 15 of the invention comprehends the production of an apparatus in which a large number of the operations to produce a cast, such as the control of the speeds of the mold, the manipulation of the mold to effect the desired 20 metal distribution, the operation of the means for transferring the molds to and from the machine, and the movement of the mold housing or hood, may be performed and controlled with great ease and convenience 25 by a single unskilled operative. From the above it will be seen that this object of the invention is attained by the remote control of the means for moving the bed and of the means for operating the mold elevating 30 mechanism and the hood, and by placing these under the control of a single operative at the station S who may also operate the speed controller 22 for controlling the speed of operation of the machine. In carrying 35 out the various steps of the method, it will be apparent that the operator will first cause the elevation of the bed by operation of the valve 75, and will then close the switch 24 to start the rotation of the mold simultaneously with the beginning of the pouring 40 operation, and will then cause the levelling of the bed by effecting a reverse operation of this valve at a predetermined stage of the pouring operation by means to be described more in detail hereinafter. This operator may thereafter manually control 45 the speed of the machine by operation of the handle 31 after the machine has attained the maximum speed. After the machine is brought to a stop, the same operator may cause the operation of the mold elevating means and the lifting of the hood by operation 50 of the control valve 46, and may thereafter cause a reverse operation of the valve 55 to bring the new mold in position for the making of a new casting.

As described in the above referred to patent, the driving motor 21 is arranged to be quickly coupled to and uncoupled from the mold 11 to permit the rapid removal of a mold and casting and a replacement of a new mold therefor, the motor being connectable to the mold by means of a coupling mechanism designated as 81 comprising a face plate 82 having attached thereto a resili-

ent or flexible plate 83 carrying a male coupling member 84 adapted to be received by a female coupling member 85 forming the end plate of the mold 11. The present invention comprehends improved means for moving the motor 21 axially to and from the mold for causing the coupling and uncoupling of the motor to the mold. In the present and preferred construction, the motor 21 is mounted on a motor base 86 slidably movable in spaced guides 87, 87, fixed to the bed of the machine, this movement being effected by means of a shaft 88 which is introduced into the ribs of the bed plate immediately under the motor base, this shaft 80 extending to one side of the machine base and provided with an operating lever 89 fixed to the extending end, the said shaft being also provided with spaced upstanding arms 90, 90, which pass up through a slot 85 in the bed plate and engage the slots 91 in the motor base 86, so that by the moving of the main lever 89 forward or backward as desired, the motor may be moved on its base to effect the coupling and uncoupling 90 operation. This movement may be accomplished very rapidly with the operator in a position where he can with one hand adjust the male coupling member to the correct position with reference to the female coupling member in the end of the flask, and with the other hand manipulate the operating lever.

To permit the pouring operation to be efficaciously carried out with the mold in the inclined position and during the levelling of the mold, the pouring spout or runner box of our invention is mounted on the bed of the machine so as to be movable therewith, the preferred construction including 100 the mounting of the runner box on the hood 57. More specifically, we provide a runner box generally designated as 92 mounted for longitudinal movement on a runner box bracket 93 which is mounted on a door 94 105 hingedly attached to an end plate 95 secured to the hood 57. The runner box 92 is preferably an all case iron construction provided with a replaceable shoe 96 made of cast iron, the wearing shoe taking up any 110 cutting action that may take place during the pouring operation, this wearing shoe being easily and cheaply replaced.

Preparatory to a pouring operation, the runner box 92 is moved from the full line 115 position shown in Figure 1, with the runner box in retracted condition, to the position shown in dotted lines in said figure, and is first cleaned by freeing the same of whatever iron splashings or "slivers" that may have 120 been left therein from the previous cast. The runner box is then painted with a carbon facing which is put on in a liquid state and owing to the temperature of the runner the moisture is immediately driven off, which 125 130

leaves the face of the runner coated with a carbon face. This tends to protect the iron runner against the cutting action of the hot metal and preserves its life, and also prevents the hot metal from sticking thereto. After the runner has been thus prepared, it is returned to the full line position shown in Figure 1, and the runner box is moved longitudinally of the bracket 93 so that the pouring spout thereof projects into the mold and more specifically into the lower portion of the opening thereof, as clearly shown in Figure 2 of the drawings, the lower end of the runner resting on the mounting therefor as shown at 97.

With the runner in this position shown in Figure 2, the pouring is begun and after the complete charge is delivered into the mold, the runner is moved to the retracted position shown in Figure 1, so that any tendency of condensation of moisture on the runner generated during a casting operation will be obviated, condensation of such moisture on the runner causing an undesirable disturbance when the hot iron is introduced therein during the next casting step. The longitudinal adjustment of the runner box is also desirable so as to permit of as close a fit between the extreme end of the runner and the mold as is possible, so as to prevent any tendency of providing a passage for iron to flow back out of the mold during the pouring step. The slideable mounting of the runner box also permits the hinging of the runner box in an efficient manner it being desirable to slip the runner into the retracted position to clear the mold before revolving the runner box to the open or dotted line position, (Figure 1). It will be understood, however, that the runner box need not be longitudinally movable and that the same may be stationarily mounted, and proper clearance provided between the mold and the portion of the runner entering the mold. In the preferred construction the runner box is removably mounted on the bracket 93 so that in changing from one size mold to another it is merely necessary to remove one size runner and replace the same with a different size runner, the quick replacement being provided by constructing the supporting bracket 93 in the form of two open guide members 93^a and 93^b.

For the purpose of preventing any chilling of the iron when a casting is made, our present invention includes the production of an all refractory surface throughout the body of the mold and at the spigot end as well as at the bell end. To provide an all refractory surface at the spigot end, the present invention includes the utilization of a refractory retainer annulus 98, (see Figure 12) and more particularly a dry sand annulus which is made of the proper diameter so that it is received by and snugly fits

into the lining 19, this annulus being placed into the mold just after the mold is faced and before the beaded configuration 99 is provided therein. To firmly retain the annulus 98 in position and to prevent the same from "backing out" of the mold when the metal is cast thereinto, the front face of the annulus 98 is notched out as at 100, (four of these notches being usually provided) to allow room for a nail to be forced into the sand lining 19 immediately under the retaining or stripper plate 101. With this construction the mold surface presents a complete sand face to the iron, and all metallic mold faces having a tendency to chill the iron are eliminated.

As heretofore indicated, the pouring of the metal is preferably accomplished automatically, the pouring operation being preferably controlled by the operator at the station S. This pouring operation is also desirably coordinated with the levelling of the machine, so that the greater portion of the metal and approximately 75% thereof is poured into the runner box while the mold is rotating at the relatively low speed and is in the inclined position and the pouring operation completed as the speed of the mold is increased and as the mold is moved from the inclined to the horizontal position, the levelling of the mold being initiated automatically by the means which controls the pouring of the metal.

The mechanism for accomplishing this coordinated operation of the pouring and levelling means is shown combinedly in Figures 1, 2, 13 and 14 of the drawings, and referring to these figures there is shown the ladle 110 mounted on trunnions 111, which may be hung from above or mounted on the machine, the said ladle being tiltable by means of a control line 112 trained over the sheaves 113, 114, spaced at opposite ends of the machine and the idler sheave 115 journaled on the standard 115', the control line being guided over the operating sheave 116 and the end thereof secured in fixed position to the pneumatic cylinder 117, the said cylinder being controlled by a valve 118 connected thereto by means of the pneumatic line 119, operation of the cylinder effecting the movement of a plunger 120 which carries the operating sheave 116. With this construction it will be seen that when the valve 118 is operated to effect the ascent of the plunger 120, the control line 112 will be pulled to tilt the ladle 110 and effect the pouring of a metal charge therein into the runner box 92, and that when the valve 118 is operated reversely, the descent of the plunger 120 will be effected, resulting in the return movement of the ladle 110 to its upright and non-pouring position.

To coordinate the pouring operation with

- the step of levelling the mold so that the mold is maintained in its inclined position for a predetermined portion of the pouring operation and so that the levelling of the mold is initiated at a predetermined point of the pouring operation as when about 75% of the pouring has taken place, the control valve 75 for the cylinders 69 and 70 is automatically operated at a given point of the movement of the plunger 120. This is shown in Figures 13 and 14 of the drawings, wherein the plunger 120 is provided with a plunger extension 121 comprising a yoke-shaped member having a plurality of sets of aligned perforations 122 adapted for selectively receiving a pin 123 movable into engagement with a lever 124 fulcrumed on a link 125 journalled in a stationary part of the valve 75, the said lever being connected to a valve plunger 126 which operates the valve 75. The valve 75 is a three-way valve of any approved construction provided with the line 76 heretofore mentioned which is connected to the bed levelling cylinders 69 and 70, and with the fluid supply line 127 and fluid discharge line 128. With this construction it will be evident that when the valve 118 is operated to effect the elevation of the plunger 120 to produce the pouring operation, at a predetermined stage of the pouring operation, the pin 123 will come into engagement with the lever 124 and effect the downward movement of the plunger 126 for operating the valve 75, the operation being such that the discharge line 128 is opened for communication with the control line 76 to effect the levelling of the mold. It will be further seen that after the pouring operation has been completed and the mold moved to the horizontal, the valve 118 may be reversely operated as mentioned to return the ladle 110 to its non-pouring position without effecting the reverse operation of the valve 75, this being due to the unidirectional cooperation between the pin 123 and the lever 124.
- After the completion of the pouring operation and the levelling operation and after the casting and the mold have been replaced by a fresh mold, the machine may be returned to its elevated position by the reverse operation of the valve 75, and to this end the lever 124 is provided with an operating handle 129 upward movement of which operates the valve 75 to close communication between the control line 76 and the discharge line 128 and open communication between the control line 76 and the supply line 127 for elevating or inclining the mold.
- It has been found desirable to positively control the rate of levelling movement of the mold in accordance with the needs of service. To this end the discharge line 128 may be controlled by means of a bypass manifold generally designated as 130 which

is provided with a plurality of bypass valves such as 131, 132, 133 and 134, all of which are closed except the one selected for use, the openings of these bypass valves being graduated by means of the bushings 131, 132, 133 and 134, progressively varying in cross-sectional area. Where a relatively slow levelling movement of the machine is desired, the relatively small bypass valve 134 will be used, and where a fast movement of the machine is desired, a larger bypass valve is selected. By this means it has been found that the speed of lowering of the machine may be mechanically controlled to a nicety.

Under normal working conditions, it has been found necessary to spin the mold after a casting operation for approximately from 4 to 8 minutes in making; for example, pipes of diameter four to six inches, this depending upon the temperature and volume of the metal introduced into the individual pipe before the walls of the pipe have sufficiently solidified to a point where the machine can be stopped and the mold removed therefrom. In order to shorten this time of spinning and to materially increase the capacities of the machines for making pipe, we prefer to subject the casting to a cooling treatment by the introduction of a supply of air into the inside of the pipe at any desired time after the metal has been poured, this air causing the metal to set more quickly and enabling the machine to be brought to a stop in about one-half the time that it would otherwise require. This air cooling step may be carried out in a number of ways, and one preferred method of performing this step is shown in Figure 11 of the drawings, in which an air line 102 is provided, the said air line being movable through the hollow armature shafting 103 of the motor 21, the said air line being advanced in the direction as shown by the arrow in said figure for ejecting a plug 104 from the head core 105 of the mold, thus providing a direct opening to the air line, the air being then turned on and the air pipe advanced through the hollow armature shaft and into the pipe to whatever distance is desired to accomplish the result.

The manner of practicing our improved process and the operation of the improved machine will in the main be fully apparent from the above detailed description thereof. It will be apparent that in performing a complete casting operation the runner box 92 is first prepared and a lined and properly faced mold is rolled into the machine into the position shown in Figure 6, after which the operator at station S manipulates the valve 46 and effects a lowering of the mold onto the supporting rollers, this operation simultaneously closing the hood 57. Another operator then couples the motor 21 to

the mold 11 by operating the lever 89 and the runner box 92 is then moved into position with the pouring spout thereof projecting into the pouring opening of the mold. 5 The operator at station S then manipulates the valve 75 to elevate the bed and mold to the inclined position. The same operator then closes the switch 24 which starts the motor running and the mold rotating at the 10 low speed, after which the operator manipulates the valve 118 to effect the pouring of the metal. After about three-quarters of the metal pouring has taken place, the valve 75 is automatically operated, causing the 15 levelling of the mold and the simultaneous increasing of the speed of operation thereof. After the mold reaches the horizontal position at or about the time the pouring operation ceases, the runner box 92 is moved 20 to the retracted position and the same operator at the station S manually controls the speed of the motor 21 by means of the control lever 31 to first reduce the speed of the mold in steps to the medium speed and to then 25 finally bring the machine to a halt. The cooling of the casting by the introduction of a stream of air therein may be carried on simultaneously with the last recited step. When the casting is sufficiently cooled, the 30 operator at the station S manipulates the valve 46 reversely, causing the elevation of the mold and the casting and the simultaneous opening of the hood, the mold then being in a position to be rolled out of the 35 machine for replacement by a new mold for a repetition of this cycle of operation. It will thus be apparent that with the improvements in the method and apparatus provided, the casting operation may be carried 40 out with considerable efficiency and with substantial economy, a casting unit being provided which is capable of being manned by a small number of unskilled laborers, and the unit operated so as to permit of the 45 production of castings in a relatively short time.

While we have described our process and shown our apparatus in the preferred manner and form, it will be obvious that 50 many changes and modifications may be made in the steps of the method and in the structure of the apparatus disclosed without departing from the spirit of the invention defined in the following claims.

55 The pivotal mounting or axis of the supporting frame 10 is described as "adjacent", that is to say near one end of the mold. This arrangement provides a balance for the 60 parts, the weight of the motor substantially balancing the weight of the parts on the opposite side of the axis, so that the tilting of the mold is comparatively easy. The arrangement also provides for the very speedy return of the mold to level position, 65 a minimum of movement being required

from the inclined to the level position. This is a feature of great importance in the casting operation, to prevent surging or waving of the metal in the mold, and to enable a smooth and vibrationless operation. 70

It will be understood that the invention relates particularly to the casting of pipes of substantial length, and usually of the bell and spigot type. During the first part of the operation, which for convenience may be described as the charging stage, the rotation of the mold is at a speed relatively low, so low that centrifugal force is insufficient to hold the metal on the mold wall. Thus uniform longitudinal distribution of the fluent metal is attained. The relatively high speed at which the mold is later rotated attains circumferential distribution. 80

We claim:—

1. In the art of centrifugally casting hollow metal bodies, the method which consists in rotating a mold at a relatively low speed while the mold is in a position inclined to the horizontal, in charging the mold with molten metal, and in moving the mold from its inclined to a substantially horizontal position while simultaneously increasing the speed of rotation thereof. 85

2. In the method of centrifugally casting hollow bodies in a rotary mold movable from a tilted to a substantially horizontal position, the step of simultaneously leveling the mold while molten metal introduced therein is still in a fluid condition and increasing the speed of rotation thereof from a relatively low to a relatively high speed. 95

3. In the method of centrifugally casting hollow metal bodies in a rotary mold movable from a tilted to a substantially horizontal position, the step of simultaneously leveling the mold while a metal charge is being introduced therein and increasing the speed of rotation thereof from a relatively low to a relatively high speed. 105

4. In the art of centrifugally casting hollow metal bodies, the method which consists in rotating a mold at a relatively low speed while the mold is in a position inclined to the horizontal, in introducing molten metal into the mold at the elevated end thereof, in moving the mold from its inclined to a substantially horizontal or level position while the metal is still in a fluid condition, and in increasing the speed of rotation of the mold during the levelling thereof. 110

5. In the art of centrifugally casting hollow metal bodies, the method which consists in rotating a mold at a relatively low speed while the mold is in a position inclined to the horizontal, in moving the mold from its inclined to a substantially horizontal or level position while simultaneously increasing the speed of rotation thereof, and in 125 130

charging the mold with molten metal while the same is in the inclined position and during the time of levelling thereof.

6. In the art of centrifugally casting hollow metal bodies, the method which consists in rotating a mold at a relatively low speed while the mold is in a position inclined to the horizontal, in moving the mold from its inclined to a substantially horizontal or level position while simultaneously increasing the speed of rotation thereof, and in introducing about 75% of a metal charge into the mold while the latter is in the inclined position, the remaining portion of

10 the charge being introduced during the time of movement of the mold from the inclined to the substantially horizontal position.

7. In the art of centrifugally casting hollow metal bodies, the method which consists in slightly inclining a rotary mold, in quickly and quietly moving the mold from its inclined to a substantially horizontal position while rotating the mold at a noncasting speed, and in delivering molten metal into the mold to charge the same while the mold is in the inclined position and during the time of movement of the mold from the inclined to the horizontal position.

8. In the art of centrifugally casting hollow metal bodies, the method which consists in inclining a rotary mold, in moving the mold from its inclined to a substantially horizontal position, and in delivering about 35 75% of a metal charge into the mold while the latter is in the inclined position, the remaining portion of the charge being introduced during the time of movement of the mold from the inclined to the substantially horizontal position.

9. In the method of centrifugally casting hollow metal bodies in a rotary mold movable from a tilted to a substantially horizontal position, the step of charging the 45 mold while the same is in a slightly inclined position and throughout the time of movement of the mold from the tilted to the horizontal position.

10. In the method of centrifugally casting hollow metal bodies in a rotary mold movable from a tilted to a substantially horizontal position, the step of introducing about 50 75% of a metal charge into the mold while the same is in the inclined position and the remaining portion of the charge while the mold is moved from the tilted to the substantially horizontal position.

11. In the art of centrifugally casting hollow metal bodies, the method which consists in rotating a mold at a relatively low speed while the mold is in a position inclined to the horizontal, in charging the mold with molten metal and in moving the mold from its inclined to a substantially horizontal position while simultaneously increasing the

speed of rotation thereof to a relatively high speed, and in then gradually decreasing the speed of rotation of the mold.

12. In the art of centrifugally casting hollow metal bodies, the method which consists in rotating a mold at a relatively low speed while the mold is in a position inclined to the horizontal, in moving the mold from its inclined to a substantially horizontal position while simultaneously increasing the speed of rotation thereof to a relatively high speed, in introducing a charge of molten metal into the mold while the same is in the inclined position and during the time of movement thereof to the horizontal position, and in then rotating the mold at a medium speed until the metal has assumed a congealed state.

13. In the art of centrifugally casting hollow metal bodies, the method which consists in rotating a mold at a relatively low speed while the mold is in a position inclined to the horizontal, in moving the mold from its inclined to a substantially horizontal position while simultaneously increasing the speed of rotation thereof to a relatively high speed, in introducing a charge of molten metal into the mold while the same is in the inclined position and during the time of movement thereof to the horizontal position, and in then reducing the speed of rotation of the mold in steps to a medium speed and continuing the said medium speed until the metal has assumed a congealed state.

14. In the method of centrifugally casting hollow metal bodies with bell ends in a rotary sand-lined mold movable from a slightly tilted to a substantially horizontal position, the steps which consist in arranging the mold with the bell end downward and pouring the molten metal toward the said end, while the mold is being quietly lowered and then rotating the mold at a speed sufficient to hold the metal on the mold 100 wall by centrifugal force.

15. In the method of centrifugally casting hollow bodies in a rotary mold movable from a tilted to a substantially horizontal position, the steps of simultaneously leveling the mold containing a metal charge while the metal is still in a fluid condition and increasing the speed of rotation thereof from a low to a high speed, in then decreasing the speed of rotation of the mold to a 115 medium speed, and maintaining the same at the medium speed until the metal congeals.

16. In the art of centrifugally casting hollow metal bodies, the method which consists in rotating a mold at a relatively low speed, in charging the same with molten metal, and in increasing the speed of rotation thereof and simultaneously imparting a further movement to the mold other than a rotary movement while the metal is still in 125 130

a fluid state to uniformly distribute the metal throughout the body of the mold.

17. In the art of centrifugally casting hollow metal bodies, the method which consists in rotating a mold at a relatively low speed, in increasing the speed of rotation of the mold and simultaneously imparting a further movement to the same other than a rotary movement, and in charging the mold with molten metal during the low and increasing speeds of rotation thereof.

18. In the art of centrifugally casting hollow metal bodies, the method which consists in rotating a mold at a relatively low speed, in simultaneously increasing the speed of rotation thereof to a high speed and imparting a further movement to the mold other than a rotary movement, and in charging the mold with molten metal, the greater proportion of the charge being introduced into the mold during the rotation thereof at the low speed and the remainder of the charge being introduced into the mold during the time that the speed of the mold is being increased.

19. In the art of centrifugally casting hollow metal bodies, the method which consists in rotating a mold at a relatively low speed while the mold is in a position inclined to the horizontal, in moving the mold from its inclined to a substantially horizontal or level position while simultaneously increasing the speed of rotation thereof, and in introducing the greater part of a metal charge into the mold while the matter is in the inclined position, the remaining portion of the charge being introduced during the time of movement of the mold from the inclined to the substantially horizontal position.

20. In the art of centrifugally casting hollow metal bodies, the method which consists in inclining a rotary mold, in moving the mold from its inclined to a substantially horizontal position, and in delivering the greater part of a metal charge into the mold while the latter is in the inclined position, the remaining portion of the charge being introduced during the time of movement of the mold from the inclined to the substantially horizontal position.

21. In the method of centrifugally casting hollow metal bodies in a rotary mold movable from a tilted to a substantially horizontal position, the step of introducing the greater part of a metal charge into the mold while the same is in the inclined position and the remaining portion of the charge while the mold is moved from the tilted to the substantially horizontal position.

22. In the art of centrifugally casting hollow metal bodies, the method which consists in rotating the mold at a relatively low speed while the mold is in a position inclined to the horizontal, in moving the mold from its

inclined to a substantially horizontal or level position while simultaneously increasing the speed of rotation thereof to a relatively high speed, in charging the mold with molten metal while the same is in the inclined position and during the time of levelling thereof, and in then reducing the speed of rotation of the mold in steps to a medium speed and continuing the said medium speed until the metal congeals.

23. In the art of centrifugally casting hollow metal bodies, the method which consists in delivering a substantial proportion of a metal charge into a mold while the latter is rotating at a relatively low speed and in introducing the remainder of the charge while the speed of rotation of the mold is increased.

24. In the art of centrifugally casting hollow metal bodies, the method which consists in delivering the greater portion of a metal charge into a mold while the latter is rotating at a relatively low speed and in introducing the remainder of the charge while the speed of rotation of the mold is increased to a relatively high speed.

25. In the art of centrifugally casting hollow metal bodies, the method which consists in delivering about 75% of a metal charge into a mold while the latter is rotating at a relatively low speed and in introducing the remainder of the charge while the speed of rotation of the mold is increased.

26. An apparatus for centrifugally casting hollow metal bodies comprising a rotary mold mounted for movement between inclined and substantially horizontal positions, means for rotating the mold, and mechanism for moving the mold from the inclined to the substantially horizontal position and simultaneously increasing the speed of rotation thereof.

27. An apparatus for centrifugally casting hollow metal bodies comprising a rotary refractory mold mounted for movement between inclined and substantially horizontal positions, means for rotating the mold, and mechanism for moving the mold from the inclined to the substantially horizontal position and simultaneously increasing the speed of rotation thereof.

28. An apparatus for centrifugally casting hollow metal bodies comprising a rotary mold and instrumentalities for uniformly distributing a charge of molten metal throughout the body of the mold comprising means for rotating the mold and mechanism for imparting to the mold a movement supplemental to the rotary movement and simultaneously increasing the speed of rotation thereof.

29. An apparatus for centrifugally casting metal bodies having bell ends, comprising a rotary mold having a bell-shaped

structure at one end and a pouring opening at the other end, and instrumentalities for uniformly distributing a charge of molten metal throughout the body of the 5 mold comprising means for rotating the mold and mechanism for imparting to the mold a movement other than the rotary movement while the metal is still in a molten condition and for simultaneously increasing 10 the speed of rotation of the mold.

30. An apparatus for centrifugally casting hollow metal bodies, comprising a rotary mold mounted for movement between inclined and substantially horizontal positions, means for rotating the mold, mechanism for moving the mold from the inclined to the substantially horizontal position, and means operated by such latter movement of the mold for increasing the speed of rotation 20 thereof.

31. An apparatus for centrifugally casting hollow metal bodies, comprising a rotary mold mounted for movement between inclined and substantially horizontal positions, means for rotating the mold, mechanism for moving the mold from the inclined to the substantially horizontal position, and means operative for increasing the speed of 25 rotation of the mold during the levelling 30 thereof.

32. An apparatus for centrifugally casting hollow metal bodies comprising a rotary mold mounted for movement between inclined and substantially horizontal positions, means for rotating the mold, mechanism for moving the mold from the inclined to the substantially horizontal position and simultaneously increasing the speed of rotation thereof, and means for charging the 35 mold with molten metal operative while the mold is in the inclined position and during 40 the levelling thereof.

33. An apparatus for centrifugally casting hollow metal bodies comprising a rotary mold mounted for movement between inclined and substantially horizontal positions, means operative for rotating the mold at a relatively low speed while in the inclined position, and mechanism for moving 45 the mold from the inclined to the substantially horizontal position and for simultaneously operating said rotating means to increase the speed of rotation of the mold to a relatively high speed.

55. 34. An apparatus for centrifugally casting hollow metal bodies comprising a rotary mold, mechanism for moving the mold between inclined and substantially horizontal positions, means for controlling the speed 60 of rotation of the mold and instrumentalities for operating the controlling means to increase the speed of rotation of the mold when the mold is moved from the inclined to the horizontal position, the said instru-

mentalities being inoperative to affect the 65 controlling means when the mold is moved from the horizontal to the inclined position.

35. An apparatus for centrifugally casting hollow metal bodies comprising a rotary mold, means for rotating the mold, 70 mechanism for moving the mold between inclined and substantially horizontal positions, means for controlling the speed of rotation of the mold, and instrumentalities operated by movement of the mold from the 75 inclined to the horizontal position for actuating the controlling means to increase the speed of the mold, the said instrumentalities being associated with the controlling means to permit the latter to be manually operated 80 to decrease the speed of the mold.

36. An apparatus for centrifugally casting hollow metal bodies comprising a rotary mold, means for rotating the mold, mechanism for moving the mold between 85 inclined and substantially horizontal positions, means for controlling the speed of rotation of the mold, and instrumentalities operated by movement of the mold from the inclined to the horizontal position for actuating the controlling means to increase 90 the speed of the mold, the said instrumentalities being associated with the controlling means to permit the latter to be manually operated to decrease the speed of the mold 95 and also to inhibit operation of the controlling means when the mold is then moved from the horizontal to the inclined position.

37. A centrifugal casting apparatus comprising a rotary mold mounted for movement between inclined and substantially horizontal positions, means for rotating the mold and mechanism for charging the mold and simultaneously moving the same from 105 the inclined to the horizontal position.

38. A centrifugal casting apparatus comprising a rotary mold and instrumentalities for uniformly distributing a charge of molten metal throughout the body of the mold 110 comprising means for rotating the mold and mechanism for imparting to the mold a movement supplemental to the rotary movement while simultaneously charging the mold with molten metal, and in a direction 115 to modify the circumferential flow of the metal due to the rotation of the mold.

39. A centrifugal casting apparatus comprising a rotary mold mounted for movement between inclined and substantially 120 horizontal positions, means for rotating the mold, mechanism for charging the mold and means operated by said mechanism at a pre-determined point of the charging step for moving the mold from the inclined to the 125 horizontal position.

40. A centrifugal casting apparatus comprising a rotary mold mounted for move-

ment between inclined and substantially horizontal positions, means for rotating the mold, mechanism for charging the mold and means automatically operable when about 5 75% of the metal has been charged into the mold for moving the mold from the inclined to the horizontal position.

41. An apparatus for centrifugally casting hollow metal bodies comprising a rotary mold mounted for movement between inclined and substantially horizontal positions, means for rotating the mold, mechanism for charging the mold and means operated by 10 said mechanism for moving the mold from the inclined to the substantially horizontal 15 position.

42. An apparatus for centrifugally casting hollow metal bodies comprising a rotary mold mounted for movement between inclined and substantially horizontal positions, 20 means for rotating the mold, mechanism for charging the mold and means operated by 25 said mechanism after about 75% of the charging operation has been effected for moving the mold from the inclined to the substantially horizontal position.

43. A centrifugal casting apparatus comprising a rotary mold, means for rotating the mold, and mechanism operable for 30 charging the mold and simultaneously increasing the speed of rotation thereof.

44. An apparatus for centrifugally casting hollow metal bodies comprising a rotary mold, means for rotating the mold, means 35 for charging the mold with molten metal, and mechanism operable by the charging means for increasing the speed of rotation of the mold.

45. An apparatus for centrifugally casting hollow metal bodies comprising a rotary mold, means for rotating the mold, means for charging the mold with molten metal, and mechanism operable by and at a predetermined point of operation of the charging 45 means for increasing the speed of rotation of the mold.

46. An apparatus for centrifugally casting hollow metal bodies comprising a rotary mold, means for rotating the mold, means 50 for charging the mold with molten metal, and mechanism automatically operable at a predetermined point of operation of the charging means for increasing the speed of rotation of the mold.

55 47. An apparatus for centrifugally casting hollow metal bodies comprising a rotary mold, means for rotating the mold, means for charging the mold with molten metal, and mechanism automatically operable after 60 about 75% of the charging operation has taken place for increasing the speed of rotation of the mold during the remainder of the charging operation.

48. An apparatus for centrifugally cast-

ing hollow metal bodies, comprising a rotary mold, and a support therefor pivoted near one end, the other end adapted to be lifted to incline the mold, and a fluid operated plunger upon which the said other end rests to be lifted thereby to incline the mold 70 and to be returned to horizontal position by gravity during the downward movement of the plunger.

49. An apparatus for centrifugally casting hollow metal bodies, comprising a rotary 75 mold, and a support therefor pivoted near one end, the other end adapted to be lifted to incline the mold, a fluid operated plunger upon which the said other end rests to be 80 lifted thereby to incline the mold and to be returned to horizontal position by gravity during the downward movement of the plunger, and remote control means for operating the plunger.

50. An apparatus for centrifugally casting hollow metal bodies, comprising a rotary mold supported at one end to be inclined by the lifting of the other end, a fluid operated plunger upon which the said other end rests to be lifted thereby and to be 85 returned by gravity during the downward movement of the plunger to uniformly distribute a charge of metal in the mold.

51. An apparatus for centrifugally casting hollow metal bodies, comprising a frame 95 or bed for removably supporting a rotary mold, the bed pivoted near one end, the other end adapted to be lifted to incline the mold, a fluid operated plunger upon which the said other end rests to be lifted thereby and to be 100 returned to horizontal position by gravity during the downward movement of the plunger, a remotely positioned control valve, and a control line connecting the control 105 valve with the cylinder.

52. An apparatus for centrifugally casting hollow metal bodies, comprising a frame or bed for supporting a rotary mold and movable between a horizontal position and a position inclined to the horizontal, a driving means for rotating the mold located on the bed at one end thereof, fluid operated means active on the other end of the bed for moving the same between the horizontal and inclined positions, and a control means in a region adjacent the first mentioned end of the bed for controlling the operation of the fluid operated means.

53. An apparatus for centrifugally casting hollow metal bodies, comprising a frame 120 or bed for supporting a rotary mold and movable between a horizontal position and a position inclined to the horizontal, means located on the bed at one end thereof for rotating the same, mechanism operative on the other end of the bed for moving the same between the horizontal and inclined posi-

tions, and means for controlling the operation of the said mechanism, said control means being located in a region adjacent the first mentioned end of the bed.

- 5 54. An apparatus for centrifugally casting hollow metal bodies, comprising a rotary mold, a supporting frame therefor, the said supporting frame being mounted for pivotal motion about an axis adjacent one end of 10 the mold, means for rotating the mold located on the frame adjacent said pivotal axis, provisions for moving the supporting frame about said axis to elevate and lower the mold, said provisions including means 15 active on the frame at the end opposite to the pivotal end thereof, and a control means therefor located adjacent the pivotal end of the frame.

55. An apparatus for centrifugally casting 20 hollow metal bodies, comprising a frame or bed for removably supporting a rotary mold and movable between a horizontal position and a position inclined to the horizontal, means located on the bed at one end thereof having a detachable connection with one end of the mold for rotating the same, mechanism operative on the other end of the bed for moving the same between the horizontal and inclined positions, a control 25 station adjacent the first end of the frame, and means at the control station for controlling the operation of said means for moving the mold between the horizontal and inclined positions.

- 30 56. In an apparatus for centrifugally casting hollow metal bodies, a movable bed for removably supporting a rotary mold, and mechanism movable with the bed for removing the mold from the bed, said mechanism comprising a fluid operated mold elevating means.

- 35 57. An apparatus for centrifugally casting hollow metal bodies, comprising a bed for removably supporting a rotary mold and movable between a horizontal position and a position inclined to the horizontal, fluid operated means for moving the bed between the horizontal and inclined positions, fluid operated means for elevating the 40 mold from the bed to remove the same, a control station, and control mechanism at said station for operating both of said fluid operated means.

- 55 58. An apparatus for centrifugally casting hollow metal bodies, comprising a bed for removably supporting a rotary mold and movable between a horizontal position and a position inclined to the horizontal, means for rotating the mold, fluid operated means 60 for moving the bed between the horizontal and inclined positions, fluid operated means for elevating the mold from the bed to remove the same therefrom, a control station and mechanism at said control station for controlling the operation of both of said

fluid operated means and the operation of the means for rotating the mold.

59. An apparatus for centrifugally casting hollow metal bodies, comprising a bed for removably supporting a rotary mold and 70 movable between a horizontal position and a position inclined to the horizontal, means for rotating the mold, means for moving the bed between the said horizontal and inclined positions, means for elevating the 75 mold for removing the same from the bed, a remote control station, and mechanism at said control station for operating the mold rotating means, the means for moving the bed, and the means for elevating the mold. 80

60. In an apparatus for centrifugally casting hollow metal bodies, a tilting bed for removably supporting the rotary mold, mechanism for removing the mold from the bed and including mold elevating means carried 85 by the bed, and remote control means for operating the said mechanism.

61. An apparatus for centrifugally casting hollow metal bodies, comprising a bed for removably supporting a rotary mold 90 and movable between a horizontal position and a position inclined to the horizontal, means for moving the bed between the horizontal and inclined positions, means for elevating the mold from the bed to remove the 95 same, a control station, and control mechanism at said station for operating both of said means.

62. An apparatus for centrifugally casting hollow metal bodies, comprising a movable bed for removably supporting a rotary mold and mechanism for removing the mold from the bed in a lateral direction, said mechanism including a mold elevating means carried by and movable with the bed. 100

63. An apparatus for centrifugally casting hollow metal bodies, comprising a bed for removably supporting a rotary mold and movable about a horizontal axis, and transfer mechanism for removing the mold laterally from the bed and replacing the same with another mold, said transfer mechanism including a mold elevating means carried by and movable with the bed. 110

64. An apparatus for centrifugally casting hollow metal bodies, comprising a bed for removably supporting a rotary mold and movable between a horizontal position and a position inclined to the horizontal, and mechanism for removing the mold from the 115 bed, said mechanism including spaced hydraulically operated means carried by and movable with the bed.

65. An apparatus for centrifugally casting hollow metal bodies, comprising a bed for removably supporting a rotary mold and movable between a horizontal position and a position inclined to the horizontal, and mechanism for removing the mold from the 120 bed, said mechanism including spaced hy- 125

- draulically operated means carried by and movable with the bed and remote control means for the said hydraulically operated means.
- 5 66. A machine for centrifugally casting hollow metal bodies, comprising a bed for removably supporting a mold, and laterally extending transfer means for removing the mold laterally from the bed and replacing 10 the same with another mold, said transfer means including an elevating track mechanism movable to a horizontal position to permit equal facility for rolling the mold laterally to or from the machine.
- 15 67. A machine for centrifugally casting hollow metal bodies, comprising a bed for removably supporting a mold, and transfer means for removing the mold from the bed and replacing the same with another mold, 20 said transfer means including laterally extending spaced pivoted elevating arms movable from an inclined descended position to a horizontal elevated position to permit equal facility for rolling the mold laterally 25 to or from the machine.
68. A machine for centrifugally casting hollow metal bodies, comprising a movable bed for removably supporting a mold laterally, and transfer means for removing the 30 mold from the bed and replacing the same with another mold, said transfer means including an elevating track mechanism movable to a horizontal position to permit equal facility for rolling the mold laterally to or 35 from the machine.
69. In an apparatus of the class described, a frame including flask supporting rollers, a hood movably associated with a flask supported thereby, and a roller carried by said 40 hood associated with said supporting rollers for rotatably supporting the flask.
70. In an apparatus of the class described, a bed, a hood movably related thereto, and spaced sets of rollers for rotatably supporting 45 a flask, each set including rollers mounted on said bed and a roller carried by said hood.
71. In an apparatus of the class described, a frame including flask supporting rollers, a hood movably associated with a flask supported thereby, a roller associated with said 50 supporting rollers for rotatably supporting the flask carried by said hood, and means for adjusting the roller on said hood.
- 55 72. In an apparatus of the class described, a bed, a hood movably related thereto, spaced sets of rollers for rotatably supporting a flask, each set including rollers mounted on said bed and a roller carried by said hood, 60 and means for independently adjusting the rollers on the hood.
73. In an apparatus of the class described, a supporting frame including flask supporting rollers, a hood movably related to said 65 frame, and rollers floatingly mounted on said hood and cooperating with the first mentioned rollers for rotatably supporting the flask.
74. In an apparatus of the class described, a supporting frame including flask supporting 70 rollers, a hood movably related to said frame, rollers floatingly mounted on said hood and cooperating with the first mentioned rollers for rotatably supporting the flask, and means for adjusting at least one 75 of the hood carried rollers.
75. In an apparatus of the class described, a bed, a hood movably related thereto, and fluid operated means for raising and lowering 80 the hood.
76. In an apparatus of the class described, a bed, a hood movably related thereto, and rollers for rotatably supporting a flask, at least one of said rollers being carried by the hood, the said hood being of sufficient weight 85 to cause the roller carried thereby to act gravitationally on the flask for stably supporting the same.
77. In an apparatus of the class described, a bed, a hood movably related thereto, and spaced sets of rollers for rotatably supporting a flask, each set including rollers mounted on said bed and a roller carried by said 90 hood, the said hood being of sufficient weight to cause the rollers carried thereby to act 95 gravitationally on the flask for stably supporting the same.
78. In an apparatus of the class described, a bed, a hood movably related thereto, and rollers for rotatably supporting a flask, at 100 least one of said rollers being carried by the hood, the said hood being of sufficient weight to cause the roller carried thereby to act 105 gravitationally on the flask for stably supporting the same, and means for raising and lowering the hood.
79. In an apparatus of the class described, a bed, a hood movably related thereto, and rollers for rotatably supporting a flask, at 110 least one of said rollers being carried by the hood, the said hood being of sufficient weight to cause the roller carried thereby to act 115 gravitationally on the flask for stably supporting the same, and remotely controlled means for raising and lowering the hood.
80. In an apparatus of the class described, a bed, flask supporting rollers carried by said bed, a roller cooperating with said 120 rollers and mounted for movement relatively thereto to permit transfer of the mold, means to floatingly connect the roller to its mounting, said means adjustable with respect to the mounting.
81. In an apparatus of the class described, a bed, flask supporting rollers mounted on 125 said bed, a roller movably related to said rollers to permit transfer of the flask, and means for floatingly supporting the roller.

82. In an apparatus of the class described, a bed, a hood movably related thereto, means for raising and lowering the hood, and a remote control means for said hood raising and lowering means. 91. In an apparatus of the class described, a bed for removably supporting a rotary mold, a hood for housing the mold adapted to be raised and lowered relatively to said bed, and mechanism for simultaneously raising the hood and elevating the mold for removal from the bed, said mechanism including spaced arms movable into engagement with the mold for elevating the same and extensions carried by said arms provided with rollers movable into engagement with the inner wall of the hood.
83. In an apparatus of the class described, a bed for removably supporting a rotary mold, a hood for housing the mold adapted to be raised and lowered relatively to said bed, and mechanism for simultaneously raising the hood and elevating the mold for removal from the bed. 10 92. In an apparatus of the class described, a bed for removably supporting a rotary mold, a hood for housing the mold adapted to be raised and lowered relatively to said bed, mechanism for simultaneously raising the hood and elevating the mold for removal from the bed, said mechanism including spaced arms movable into engagement with the mold for elevating the same and extensions carried by said arms provided with rollers movable into engagement with the inner wall of the hood. 75
84. In an apparatus of the class described, a bed for removably supporting a rotary mold, a hood for housing the mold adapted to be raised and lowered relatively to said bed, and mechanism operative for effecting a raising and lowering of the hood simultaneously with an elevating and descending movement of the mold respectively. 15 93. In an apparatus of the class described, a bed for removably supporting a rotary mold, a hood for housing the mold adapted to be raised and lowered relatively to said bed, and unitary mechanism for simultaneously raising the hood and elevating the mold for removal from the bed. 80
85. In an apparatus of the class described, a bed for removably supporting a rotary mold, a hood for housing the mold and adapted to be raised and lowered relatively to said bed, and unitary mechanism for simultaneously raising the hood and elevating the mold for removal from the bed. 85
86. In an apparatus of the class described, a bed for removably supporting a rotary mold, a hood for housing the mold adapted to be raised and lowered relatively to said bed, and fluid operated mechanism for simultaneously raising the hood and elevating the mold for removal from the bed. 90
87. In an apparatus of the class described, a bed including rollers for removably supporting a rotary mold, roller means associated with said rollers and movable relatively thereto for releasing the mold, and fluid operated mechanism for simultaneously raising the said roller means and elevating the mold for removal from the rollers. 95
88. In an apparatus of the class described, a bed for supporting a rotary mold, a hood for housing the mold adapted to be raised and lowered relatively to the bed, and fluid operated mechanism for effecting the raising and lowering of the hood. 100
89. In an apparatus of the class described, a movable bed for supporting a rotary mold, a hood for housing the mold adapted to be raised and lowered relatively to said bed, and fluid operated mechanism carried by the bed for effecting the raising and lowering of the hood. 105
90. In an apparatus of the class described, a bed for supporting a rotary mold, a hood for housing the mold adapted to be raised and lowered relatively to said bed, and mechanism for effecting the raising and lowering of the hood comprising means normally housed by the hood and movable into and out of engagement with the inner wall of the hood. 110
91. In an apparatus of the class described, a bed for removably supporting a rotary mold, a mold enclosing hood movably carried by the bed, and a runner box carried by the bed. 115
92. In an apparatus of the class described, a bed for supporting a rotary mold movable between inclined and horizontal positions, and a mold enclosing hood carried by and movably mounted on the bed. 120
93. In an apparatus of the class described, a bed for removably supporting a rotary mold, a mold enclosing hood movably carried by the bed, and a runner box carried by the hood. 125
94. In an apparatus of the class described, a bed for supporting a rotary mold movable between inclined and horizontal positions, and a mold enclosing hood carried by and movably mounted on the bed. 130
95. In an apparatus of the class described, a bed for removably supporting a rotary mold, a mold enclosing hood movably carried by the bed, and a runner box carried by the hood. 135
96. In an apparatus of the class described, a bed for supporting a rotary mold movable between inclined and horizontal positions, a mold enclosing hood carried by and movably mounted on the bed, and a runner box carried by the hood. 140
97. In an apparatus of the class described, a bed for removably supporting a rotary mold, a mold enclosing hood movably carried by the bed, and a runner box mounted on the hood for swinging motion relatively to the mold. 145
98. In an apparatus of the class described, a bed for removably supporting a rotary mold, a mold enclosing hood movably carried by the bed, and a runner box mounted on the hood for slideable and swinging motion relatively to the mold. 150
99. In an apparatus of the class described, a bed for supporting a rotary mold movable between inclined and horizontal positions, a mold enclosing hood carried by and mov-

- ably mounted on the bed, and an all cast iron runner box carried by the hood. 65
100. In an apparatus of the class described, a bed for supporting a rotary mold, 5 an all cast iron runner box having a replaceable shoe carried by the bed and mounted on the bed for rotary and longitudinal movement relative to the mold supported by the bed. 70
101. In an apparatus of the class described, a hood, an end plate thereon, a mounting swingingly mounted on said end plate, and a runner box slidably carried by said mounting. 75
102. In an apparatus of the class described, a hood, an end plate thereon, a mounting swingingly mounted on said end plate, and a runner box slidably and removably carried by said mounting. 80
103. A refractory mold comprising a flask having a refractory lining and a refractory retaining annulus at the spigot end of the flask associated with said lining, the construction being such that an all refractory surface is provided at the spigot end of the mold. 85
104. A refractory mold comprising a flask having a refractory lining, a lining retaining ring secured to the flask at the spigot end thereof, and a refractory retaining annulus received by said lining and anchored against said retaining ring, the construction being such that an all refractory surface is provided at the spigot end of the mold. 90
105. A refractory mold comprising a flask having a moist sand lining and a dry sand annulus associated with the lining and arranged at the spigot end of the flask, the construction being such that an all refractory surface is provided at the spigot end of the mold. 95
106. In the method of centrifugally casting hollow metal bodies with bell ends in a rotary sand-lined mold, movable from a slightly tilted to a substantially horizontal position, the steps which consist in arranging the mold to tilt upon an axis near the bell end, pouring the molten metal toward the said end while the mold is being lowered, then increasing the speed of rotation of the mold to apply the metal to the wall thereof by centrifugal force, and then gradually decreasing the speed. 100
107. The method of centrifugally casting hollow metal bodies which consists in charging a mold with molten metal, in moving the mold from an inclined to a horizontal position while the metal is still in a fluid condition, and in thereafter introducing a cooling fluid into the mold. 105
108. The method of centrifugally casting hollow metal bodies which consists in charging a rotary mold closed at one end thereof with molten metal, in imparting to the mold 110
- a movement supplementary to the rotary motion thereof while the metal is still in a fluid condition, and in thereafter opening the closed end of the mold and introducing a circulating supply of cooling fluid into the mold. 115
109. An apparatus for centrifugally casting hollow metal bodies comprising a rotary mold, means for rotating the same, means for moving the same from an inclined to a horizontal position while the metal charged into the mold is still in a fluid condition, and means for thereafter introducing a circulating supply of cooling fluid into the mold. 120
110. An apparatus for centrifugally casting hollow metal bodies comprising a rotary mold closed at one end thereof, means for rotating the same, means for imparting to the mold a movement supplemental to the rotary movement while the metal is still in a fluid condition, and means for opening the closed end of the mold and introducing a circulating supply of cooling fluid into the mold. 125
111. A refractory mold comprising a flask having a bell end and a moist sand lining, and having a dry sand annulus associated with the lining and arranged at the spigot end of the flask, the construction being such that an all refractory surface is provided. 130
112. In a centrifugal casting machine, a frame for supporting a mold, said frame including pairs of rollers upon which the mold is rotatable, a roller cooperating with each pair above the mold to hold the mold thereto, and a common means for lifting the upper rollers. 135
113. In a centrifugal casting machine, a frame for supporting a mold, said frame including pairs of rollers upon which the mold is rotatable, a roller cooperating with each pair above the mold to hold the mold thereto, and a connection between said last named rollers to enable the simultaneously lifting thereof. 140
114. In the art of centrifugally casting hollow metal bodies, the method which consists in rotating a mold, in imparting to the mold a further movement other than a rotary movement while a metal charge therein is still in a fluid state, and in operating the mold during said further movement by first rotating the same at a relatively low speed during part of the period of such movement and by then increasing the speed of rotation of the same during another part of the said period. 145
115. In a centrifugal casting machine, a mold support, a mold rotatably carried on the support, a hood cooperating with the support to rotatably hold the mold in place, means to lift the mold from the support including rails upon which the mold may roll laterally from and to the support, means to 150

lift the rails, and means in connection with the rails for lifting the hood when the rails are lifted.

116. The step in the method of casting centrifugally in tilting refractory molds inclined to facilitate charging, and substantially level during casting, which consists in rotating the mold during the greater part

of the leveling and metal charging operation, at a speed such that the metal will not be held against the mold wall.

Signed at Birmingham in the county of Jefferson and State of Alabama this 26th day of July A. D. 1923.

WILLIAM D. MOORE.
WALTER MORGAN.
